UNITED STATES PATENT OFFICE.

SETURÔ NAGAO, OF TOKYO, JAPAN.

UNLOADING MACHINE.

Original application filed December 16, 1925, Serial No. 75,705, and in Japan December 17, 1924. Divided and this application filed August 11, 1926. Serial No. 128,659.

My invention relates to improvements in an unloading machine having guide-bars for the vertically movable grab. My invention comprises the provision of an operator's cage and 5 scraping boards at the bottom portion of said guide-bars. These guide-bars themselves are also guided by a fixed frame so that they may be vertically adjusted by the operator according to the position of the material to be han- 10 dled.

The objects of my invention are as follows:

1. To permit the grab to handle the material at any desired point of its scope with the aid of the guide-bars, without shaking or entangling 15 the ropes by which the grab is suspended.
2. To enable the operator easily to overlook everything in front of him, by attaching the operator's cage to the guide-bars.
3. To complete the scraping or scavenging 20 of the material by means of the scraping board at the bottom portion of the guide-bars.
4. To attain automatic operation in the case of driving by an electric motor by attaching one electric terminal to the lower end of 25 one guide-bar and the other, to the fixed frame in accordance with the highest or discharging position of the grab or corresponding position of a counter weight on the chute, and the third to any other required part. The 30 two former are actuated by the motion of the grab and the remainder by the motion of the grab jaws, or the corresponding relative movement of the operating ropes.

I will now describe my invention in connection with the accompanying drawings, in which

Fig. 1 is an elevation showing by way of example the assembled apparatus combined with a belt-conveyor when unloading from a barge.

Fig. 2 is a side elevation of the view shown in Fig. 1; Fig. 3 is a plan of the same.

Fig. 4 is an elevation showing my unloading machine; Fig. 5 is a side elevation of the same.

Fig. 6 shows an elevation of the guide-bars, Fig. 7 a plan of lower portion thereof, and Fig. 8 a plan of the upper portion.

Fig. 9 shows an elevation of the scraping board and Fig. 10 a side elevation of the same.

Fig. 11 is a diagrammatic sketch showing an automatic operating device for my machine.

Similar letters indicate similar parts in the 55 different drawings.

Referring to Fig. 1, a frame 5 is movably mounted on the truck 6 which is movable parallel with the edge of the wharf. The said truck is moved by a motor 61. The vertical guide-bars 4 by which the grab 1 is guided, 60 and an automatic swinging chute 2 are fixed on one end of said movable frame, said chute being pivoted at 21. The hoist 500 of the grab and the counter weight 44 of the guide-bars 4 are placed on the other end. The said counterweight and guide bars are connected by a 65 rope 42 passing over a pulley 43.

A belt conveyor 30 contained by the frame 5 conveys horizontally the material dropping from an open hopper 3 disposed below the 70 chute 2.

As a tripper 31 of the belt conveyor is attached to a chute 32 on the truck 6, the material may be carried away from the belt conveyor to the chute and finally by means of a 75 long belt 33 along truck rails on the ground to the destination.

I will, first, describe the action of the grab and the automatic swinging chute herein-after.

Referring to Figs. 4 and 5, the grab 1 comprises a frame 17 provided at its opposite ends with guide shoes 15 adapted to travel in channel-shaped guideways formed in the guide bars 55. Suspended from said frame is a 85 grab 1 comprising a pair of jaws 13 pivoted to the frame adjacent to its lower edge, said jaws being connected together by a pair of links 13^a, one secured to each of the jaws, said links being pivotally connected together at 90 their free ends the organization being such that the jaws are closed and opened respectively by raising and lowering the pivoted ends of the links. For this purpose a cable 11 secured at one end to a windlass 500 (Fig. 95 1) passes over a pulley 110 (Fig. 4) and is secured at its opposite end to the pivoted ends of the links. Mounted on the pivot of said links is a pulley 13^b, and in vertical alinement therewith a pulley 17^a is mounted on a pivot 100 carried by the frame 17, the cable 11 being guided on said pulleys, as shown in Fig. 4, so that by winding the cable 11 on the windlass the pivoted ends of the links will be raised, thereby closing the jaws, as will be readily 105 understood. An auxiliary cable 12 is secured at one end to the frame 17, passes over a pulley 120, and is connected at its opposite end to another drum carried by the windlass 500. Assuming that the grab has been lowered in 110

open condition to the bottom of the frame 4, as shown in dotted lines in Fig. 4, as the rope 11 is wound up, the jaws will be brought together, thus scooping up the material which is intended to be raised. Upon continued winding of the rope, the grab will ascend, and when a predetermined position is reached, the top portion of the grab will engage with a counterweight 200 connected to the lower end 22 of the chute 2 by ropes 23 and 230 passing over pulleys 26, 260, 25 and 24, and raises the said weights thereby causing the ropes 23 and 230 to slacken so that the chute will swing on its pivot into the inclined position shown in full lines in Fig. 5, with its upper, heavier portion extending beneath the grab and its lower end 22 within the open hopper 3, the swinging movement of the chute being limited by a cable 240 attached at one end to the frame 5 and at its opposite end to the extreme upper end of the chute. It will be understood that the chute is normally retained in vertical position by the counterweight 200.

25 After winding to a certain extent the action ceases and the auxiliary rope 12 of the grab following the motion of the main rope 11 is braked. Hence the grab discharges its contents on the chute 2 by the action of gravity on the grab jaws as well as the releasing action of the main rope 11.

By releasing the brake on the auxiliary rope, the grab is then lowered down to the material to be handled, and thus one cycle of handling operations of the grab is completed.

In order to insure that the chute 2 has swung entirely out of the way of the grab when the latter is descending, means is provided for causing the weight 200 to descend with the grab during the first part of the downward movement of the latter. This means, as shown somewhat diagrammatically in Fig. 5, comprises a pair of bell cranks pivoted to the counterweight 200 at each side thereof, the depending arms 211 of said bell cranks being hook-shaped at their lower ends and adapted to engage lateral flanges formed at the top edge of the grab frame 17. The outer portions of the hooks are rounded so that on the upward movement of the grab the lateral flanges of the frame 17 will engage said rounded ends and swing the bell cranks on their pivots and thus permit said flanges to pass, whereupon, by means of counterweights 212 on the horizontal arms of the bell cranks, the hooks at their lower ends engage beneath the said lateral flanges so that when the grab starts to descend it will carry the weight 200 with it. When the grab has descended a sufficient distance to insure that the chute has been swung into vertical position, the hooks 211 "ride" upon wedge-shaped lugs 50 formed on the guide bars 55 and release the flanges of the grab frame, thus leaving the grab free to continue its descent.

It is important that this invention comprises the vertical guide-bars guiding the grab and the counterweight of the chute.

These guide-bars may be constructed by a long single bar or two bars consisting of the upper fixed bar 55 fixed to the frame 5 and the lower movable bar 4 situated in telescopic relation to the fixed bar 55 and sliding therein as shown in the drawings.

Referring to Figs. 6 and 7, the bottom ends of the movable guide-bars form a rectangular frame 41, and an operator's cage 40 is installed on one side of the frame.

In this cage the operator can safely operate the whole apparatus, observing the material to be handled in front of him.

The lower portion 4 of the guide-bars can be moved up and down, according to the position of the material to be handled, by winding with a winch 46 the rope 45 connected to the frame 5.

A scraping board is attached to the bottom of the guide-bars by which the gathering and scavenging of material at the bottom of a barge is to be accomplished.

In the drawings, two scraping boards 401 and 411 are provided on two adjacent sides of the bottom frame 41 of the guide-bars. To gather the material having escaped from the grabbing of the grab, one of the scraping boards 411 is brought into operation by the travel of the truck 6 and the other 401 by the motion of the frame 5 mounted on the truck 6.

Each of the edges at either end of the scraping board 401 or 411 forms a trunnion 403, which is journaled in an aperture of a vertical spindle 406 supported in the frame 41. And the scraping board can not rotate in the inner direction owing to the engagement of a lug 402 projecting from the board with an elongation 405 extending from the end of the vertical spindle 406. When the board in the course of its scraping meets with any obstacle at the bottom of the barge, the spring 409 which normally pulls the board inwards, expands, until the board inclines outwards and passes safely over such obstacle.

The spring 407 absorbs the shock due to the lowering guide-bar striking the bottom of the barge and also serves as a means for effecting a complete scraping.

Referring to Fig. 11, which diagrammatically shows the automatic operation of the grab, there are three sets of electric terminals, having relations with relays and other useful apparatus on the distributing electrical panels on the machine room. The first set 7, fixed on the bottom portion of the guide-bar, is adjustable according to the position of the material and, being actuated by the projection 184 of the descending grab, causes the grab to ascend. The second set 72 is attached to the point of the fixed frame corresponding to the highest position of the counter weight 200 of the swinging chute, and, when this terminal

set is actuated by the projection 282 of the ascending counterweight 200 and the upward motion of the grab is stopped, the auxiliary rope is braked and the main rope is released 5 thus causing the grab to open. The third set 71 may be actuated, for example, by the turning motion of the projection 14 carried by the grab jaws 13, when the grab is open as shown in the drawing, or by the relative 10 movement of the auxiliary and main ropes.

With the above arrangement of the electric terminals, soon after the grab descends on to the material to be handled, engagement of the projection 184 and the first terminal 7 completes 15 the circuit for a motor driving the drum to wind the main rope, and the grab ascends grasping the material and lifts up the counter weight of the chute to a predetermined position, where the second terminals 72 are actuated by the ascending counterweight. The engagement of the projection 282 and the terminals 72 causes the grab to stop, the auxiliary rope to be braked, the main rope to be released, and the grab to be opened to discharge 20 the material on the chute. After it is fully opened, the grab descends again onto the material to be handled, by the engagement of the projection 14 and the third terminals 71, or by the like engagement through the 25 relative movement of the main and auxiliary ropes.

By repeating such operations as above described, the complete automatic handling operations are readily attained.

30 My invention is applicable not only for the

double rope grab as above described, but also for the single rope grab or any other bucket or skip.

With my invention it is possible to use as prime mover, not only an electric motor, but 40 any heat engine.

What I claim as new and desire to secure by Letters Patent of the United States, is:

A device of the character described, comprising, in combination, a fixed frame, vertically disposed guide bars supported in said frame, a vertically movable grab disposed between said guide bars and adapted to be guided thereby during its vertical movements, and electrical means for automatically operating said grab and comprising a pair of terminals carried by said guide bars at the lower ends thereof, said terminals being in electrical connection with a source of power, means carried by the grab for closing the circuit 45 through said terminals when the grab has reached its lowermost position, a second pair of terminals disposed on said frame in the path of said grab, and a third pair of terminals disposed in position to be operated by 50 said grab during its opening movement, the closing of the circuit through the respective terminals being effective to raise the grab from its lowermost to its highest position, to cause the grab to be opened to discharge material therefrom, and to cause the descent of 55 said grab to its lowermost position.

In testimony whereof I affix my signature.

SETURÔ NAGAO.
